CONVERTIBLE SCREEN AND TABLE

Edwin Frederick Otto Reller, Evansville, Ind.

Application June 20, 1932. Serial No. 618,326

4 Claims. (Cl. 45—116)

This invention relates to a convertible table and screen and has for an object to provide an improved convertible table and screen which may be quickly and easily converted from table use 5 to screen use and vice versa.

A further object of this invention is to provide an improved convertible table and screen which carries smoking utilities and is usable both as a card table, smoking table or pedestal. 10 Yet an additional object of this invention is to provide a convertible table or screen wherein the table top is made up of several sections which are removable from the top of the table and when removed cooperate with the sides of the table to 15 form a screen.

Still another object of this invention is to provide a convertible table and screen of very sturdy construction which may be made entirely of metal if desired, and wherein the principal supporting 20 members are channel bars and angle bars.

With the foregoing and other objects in view, as will hereinafter become apparent, this invention comprises the constructions, combinations and arrangements of parts, hereinafter set 25 forth, disclosed and shown on the accompanying drawing. In this drawing,

Figure 1 is a front elevation of the invention used as a screen, the middle plate being shown raised in broken lines,

30 Figure 2 is a top plan view of Figure 1 showing three sliding plates in position within channel iron frame,

Figure 3 is a front elevation of the invention used as a card table,

35 Figure 4 is a sectional view taken on line 4—4 of Figure 5,

Figure 5 is a rear view of the table, the top plate broken away to show slide or guide members for holding the plates, and

40 Figure 6 is a side elevation of the table, the top plates broken away to show guide members.

There is shown at 10 the convertible table and screen constituting this invention in use as a screen, while at 11 the invention is shown in use 45 as a table, card table, smoking stand, or pedestal.

The screen 10 consists of three channel frames 12, 13 and 14 hinged together as at 15. Each channel frame consists of two channel or U-shaped bars 16 and 17, forming uprights and 50 connected by cross bars 18 and 19. The bars 16, 17, 18 and 19 may be made from any suitable material, either of wood, or of metal such as iron, or if desired of a lighter metal such as aluminum, or any other suitable metal or mate- 55 rial.

In the same manner all of the remaining elements yet to be described may be likewise made of the same or other suitable material or metal.

The bar 19 connects the channel members 16 and 17 in such a manner so as not to obstruct 60 the channel in the channel bars 16 and 17, while the bar 18, suitably spaced from the bottom of the upright channel bars 16 and 17, obstructs the channels near the bottom of the upright bars 16 and 17 and thus form a support for the removable 65 panels 20, 21 and 22. At 21' the panel 21 has been shown in partly removed position, it being only necessary to raise up the panels 20, 21 and 22 to the top of the channel frames 12, 13, and 14 to remove them therefrom, and vice 70 versa to place them in position.

The screen 10 may be used either as a straight screen or may be folded somewhat about the hinges 15 to give it any desired angle for suitable use in the household.

To convert the screen 10 into the table 11 the panels 20, 21 and 22 are raised upwardly to remove them from the channel frames 12, 13 and 14. A table top carriage 24 is hinged to the top of the middle channel frame 13 at 25. The 80 table top carriage 24 consists of a pair of angle bars 26 joined together by another pair of angle bars 27. The carriage 24 having been folded upwardly around its hinges 25, the channel frames 12 and 14 are closed about hinges 15 until 85 they are at right angles with the channel frame 13, whereupon a latch bar 28 hinged at 29 to the channel frame 12 is latched over the hook 30 on channel frame 14. In this position the channel frames 12, 13 and 14 provide the supporting legs 90 for the table, and to reinforce the table, an additional latch bar 31 slotted as at 32 is secured by thumb screws 33 across from the channel frame 12 to the channel frame 14. The top portion of this latching bar 31 serves as a further 95 support for the table top carriage 24, the table top carriage 24 being thus supported on one side by its hinges 25 and on the other side by the latch bar 31, as well as the top end of the uprights 16 and 17.

The panels 20, 21 and 22, which are now used as table top panels each have a pair of angle bars 34 secured to the bottom thereof and cooperating with the angle bars 27 to act as complementary thereto. The panel 21 is placed over 105 the table top carriage 24 and its hook members 34 are placed under the hook members 27 of the carriage and the panel 21 is slid to the middle of the table. Then panels 20 and 22 are placed on opposite sides of the panel 21 in the same 110

manner, thus forming a complete table top consisting of the three panels 20, 21 and 22.

Channel members 12 and 14 are each provided on the inside thereof with shelves 35 supporting compartment 36, the compartment 36 being usable for holding smokers' articles, playing cards, sewing articles, or other similar household articles, and when the channel frames 12 and 14 are folded about to provide legs for the table 11, 10 the shelves 35 complement each other and form a complete square shaped shelving below the level of the table top.

The novel features and the operation of this device will be apparent from the foregoing disclosure. While the device has been shown and the structure described in detail, it is obvious that this is not to be considered limited to the exact form disclosed, and that changes may be made therein within the scope of what is claimed, 20 without departing from the spirit of the invention.

Having thus set forth and disclosed the nature of this invention, what is claimed is:

1. A table comprising a plurality of channel frame members hinged together, a plurality of panel members, a table top carriage member secured to one of said channel frame members, means for securing said frame members at an angle to each other to provide table legs, and 25 means on said channel members cooperating with said table top carriage member to hold said panel members on said table top carriage member to provide a table top, said channel frame members being adjustable to any desired angle 30 and being adapted to receive said panels within the channels of the frames to provide an adjustable screen.

2. A table comprising a plurality of channel frame members hinged together, a plurality of panel members, a table top carriage member secured to one of said channel frame members, means for securing said frame members at an angle to each other to provide table legs, means 40 on said channel members cooperating with said table top carriage member to hold said panel members on said table top carriage member to provide a table top, and shelf means on one of said channel frame members to provide a utility shelf for said table, said channel frame members 45

50

being adjustable to any desired angle and being adapted to receive said panels within the channels of the frames to provide an adjustable screen.

3. A table comprising a plurality of channel frame members hinged together, a plurality of panel members, a table top carriage member secured to one of said channel frame members, means for securing said frame members at an angle to each other to provide table legs, means on said channel members cooperating with said table top carriage member to hold said panel members on said table top carriage member to provide a table top, and shelf means on some of said channel frame members, said shelf means complementing each other to form a complete intermediate utility shelf when said channel frame members are at the angle to each other to provide a table support, said channel frame members being adjustable to any desired angle 95 and being adapted to receive said panels within the channels of the frames to provide an adjustable screen.

4. A table comprising three upright channel frame members, hinge means securing two of 100 said channel frame members to the opposite side of the third channel frame member, each channel frame member comprising a pair of oppositely disposed upright channel bars and a pair of cross bars securing said upright channel bars 105 together, the lower cross bar providing a slot in the channel of the channel bars, a plurality of panel members, a table top carriage member hinged to said third channel frame member, and a shelf member secured to each of the other two 110 channel frame members, latch bars for securing together said two outer channel frame members at right angles to said third channel frame member with said table top carriage member supported on said frame member, angle bars forming part of said table top carriage member, and cooperating oppositely disposed angle bars on each panel member, whereby said panel members may be placed on said table top carriage member to provide a table top therefor, and 120 whereby the shelf members complementing each other to provide an intermediate utility shelf for the table.
